UNITED STATES PATENT OFFICE.

CHARLES DI COMO, OF RAHWAY, NEW JERSEY, ASSIGNOR OF ONE-HALF TO GEORGE MEIR, OF RAHWAY, NEW JERSEY.

REWINDING APPARATUS.

1,419,826.

Specification of Letters Patent. Patented June 13, 1922.

Application filed April 15, 1921. Serial No. 461,468.

To all whom it may concern:

Be it known that I, CHARLES DI COMO, a citizen of the United States, and a resident of Rahway, in the county of Union and State 5 of New Jersey, have invented a new and Improved Rewinding Apparatus, of which the following is a full, clear, and exact description.

This invention relates to re-winding devices and particularly to an improved re-winding device for use by barbers for re-winding paper and has for an object to provide a simple construction which is inexpensive but which will readily re-wind paper according to the desire of the operator.

Another object of the invention is to provide a re-winding device which will act to provide a number of small rolls from a large roll of paper, the arrangement permitting 20 an easy removal of the re-wound rolls.

A still further object of the invention is to provide a re-winding device having means for supporting a large roll and holding the same against rotation under the 25 action of momentum and at the same time providing a readily removable re-winding bar which may be operated through a multiplying mechanism or by a direct crank action.

30 In the accompanying drawing—

Figure 1 is a perspective view of a re-winding device disclosing an embodiment of the invention.

Figure 2 is a fragmentary sectional view 35 through Figure 3 on line 2—2.

Figure 3 is a fragmentary side view of the upper part of one side of the front end of the device shown in Figure 1, the same illustrating a rod locking catch.

40 Figure 4 is a fragmentary view partially in section showing a modified arrangement of driving means for the re-winding rod.

Referring to the accompanying drawing by numerals, 1 indicates a frame which may 45 be of cast metal or of any desired material, but preferably comparatively heavy for its size so that it may readily remain in place during the operation of the crank 2 and associated parts. The frame 1 is provided 50 with posts 3 and 4 at the rear having notches 5 and 6 for receiving the restricted ends of the roller 7. Roller 7 carries a large roll 8 of paper which is to be re-wound on the rod 9 so as to form a number of small 55 rolls 10.

In barber shops where this device is intended to be used, small rolls similar to roll 10 are provided for the fitting in back of a barber chair and used as wiping paper for the razor. In this fitting the large roll 60 8 could not be used but only small rolls similar to roll 10.

The paper when made at the factory is wound in large rolls similar to roll 8 so that at some time it must be re-wound into 65 a number of small rolls 10. In the ordinary barber shop, there are periods when one or more of the barbers are not working and at these slack times the re-winding device embodying the invention may be operated to 70 provide any number of small rolls 10 without any additional expense to the barber. Under the present system, small rolls 10 may be purchased but they are very much more expensive than the large roll 8 and as small 75 rolls may be wound by the barber without additional expense and said rolls may be of any desired diameter according to his own particular wish, the apparatus will produce a saving without adding any expense except the purchase price of the apparatus.

When using the device, the spring pressed bar 11 is raised and the roller 7 with its roll 8 inserted as shown in Figure 1 and end bar 11 released which will provide the desired tension and prevent the roller 7 from rotating under momentum. Bar 11 is a U-shaped bar pivotally mounted at 12 and 13 on the braces 14 and 15 and continually 80 acted on by retractile springs 16 and 17. 90 After the roll 8 has been properly positioned it is unwound manually to a certain extent and looped over the bar 9 and held by the fingers until said bar has rotated one or more times after which the bar is rotated 95 fast or slow as desired and as many revolutions as desired for producing the small roll 10. When the small roll 10 has been produced, the paper is torn or cut between the rolls 8 and 10 and the roll 10 removed 100 and a new roll started. In order to remove the roll 10, the bar 9 must be removed. Bar 9 is provided with an annular groove 18 (Fig. 2) in which the spring catch 19 fits, 105 said catch being held in place by suitable screws 20 with an overlapping end 21 and a finger hold 22. When the parts are arranged as shown in Figure 1, the finger hold 22 is pressed toward the upright or post 3 which will cause the catch 19 to move 110

out of groove 18 whereupon the pinion 23 rigidly secured to shaft 9 may be grasped and the bar 9 pulled longitudinally out of the uprights 24 and 25 and out of the roll 10. As soon as the bar 9 has been thus removed the roll 10 will fall down or be released for removal. The pinion 23 meshes with a gear wheel 26 rigidly secured to a stub shaft 27 journaled in the upright 24 and held in place by any suitable means, said shaft having the crank 2 rigidly connected therewith whereby the gear wheel 26 may be rotated freely. As gear wheel 26 is much larger than pinion 23, the action of crank 2 is multiplied and the bar 9 is rotated at a comparatively high speed. In case it should not be desirable to use this multiplying mechanism, the shaft 9 could be rigidly connected with the stub shaft 27 whereby the bar 9 will rotate at the same speed as the crank 2.

What I claim is:

A re-winding apparatus of the character

described, comprising a body having two pairs of uprights, one pair of said uprights having a slot on the upper end thereof, each upright of said pair having a supporting bar provided with an opening on the upper end thereof, a U-shaped member pivotally secured to said bars and straddling the entire space between said uprights of said pair, a spring acting on said U-shaped members for pulling same downwardly, a roller carrier having an annular groove on each end thereof and fitting in said slots, a roll of paper mounted upon said roller frictionally held from accidental rotation from said U-shaped member, a round opening for each of the other uprights, a pinioned roller for said round openings, said roller having an annular groove on one end thereof for receiving a manually retracted holding finger to prevent said roller from longitudinal movement, and a handle to rotate said roller.

CHARLES DI COMO.
